UNITED STATES PATENT OFFICE.

OTIS A. MYGATT, OF NEW YORK, N. Y.

DESIGN FOR A SHADE, REFLECTOR, OR SIMILAR ARTICLE.

45,949.

Specification for Design.

Patented June 16, 1914.

Application filed June 5, 1908. Serial No. 437,004. Term of patent 14 years.

To all whom it may concern:

Be it known that I, OTIS A. MYGATT, a citizen of the United States, residing at New York, in the county of New York and State of New York, have invented a new, original, and ornamental Design for Shades, Reflectors, or Similar Articles, of which the following is a specification, reference being had to the accompanying drawing, forming part thereof.

As shown in the drawing, my design consists of a shade or reflector circular in plan and having a cylindrical skirt portion. The skirt portion is provided on its outer surface with vertical, contiguous rows of pearls and on its inner surface with vertical rows of prisms. The prisms are the same width

as the rows of pearls and are radially opposite the same.

I claim—

The ornamental design for a shade or reflector or similar article circular in plan and having a cylindrical straight sided skirt portion, the outer surface of the said skirt portion being provided with vertical rows of pearls and the inner surface thereof being provided with vertical prisms of the same width and radially opposite said rows of pearls as shown and described.

OTIS A. MYGATT.
